UNITED STATES PATENT OFFICE.

LOUIS D. VOGEL, OF OMAHA, NEBRASKA.

WOODWORKING-MACHINE.

SPECIFICATION forming part of Letters Patent No. 654,296, dated July 24, 1900.

Application filed December 19, 1899. Serial No. 740,930. (No model.)

To all whom it may concern:

Be it known that I, LOUIS D. VOGEL, a citizen of the United States, residing at Omaha, in the county of Douglas and State of Nebraska, have invented a new and useful Woodworking-Machine, of which the following is a specification.

My invention relates to woodworking-machines especially designed for crozing, howeling, and trimming the ends of tubs, pails, and other wooden vessels of circular cross-section.

One object in view is to provide a revolute work-head which by a few easily-performed changes may be adjusted to receive and carry different sizes and shapes of wooden vessels.

A further object is to provide a cutter-carrying mechanism which may be adjusted quickly toward or from the work, so as to permit the latter to be applied to or removed from the work-head without hindrance from the cutter mechanism, and to also provide for a proper movement of the cutter mechanism into operative relation to or engagement with the work.

25 A further object is to provide means for regulating the adjustment of the cutter mechanism within certain fixed limits, according to the size or diameter of the work under treatment; but this limit of adjustment is variable 30 under certain changes in the operating devices to the end that the cutters may be adjusted properly to work which varies in diameter.

With these ends in view the invention consists in the novel combinations of mechanisms and in the construction and arrangement of parts comprising such mechanism, as will be hereinafter fully described and claimed.

In the accompanying drawings I have represented a woodworking-machine which embodies the several features of my invention in their preferred form, and to these drawings I shall now refer in order to explain more clearly the nature of the invention and the 45 manner in which the same is or may be carried into effect.

Figure 1 is a plan view of a woodworking-machine embodying my invention. Fig. 2 is an elevation of the machine looking at the 50 side on which the drop-weights are located. Fig. 3 is a vertical transverse section through the machine in the plane of the dotted line 33

on Fig. 1. Fig. 4 is a detail transverse sectional elevation through one of the transversely-movable carriers and parts associated therewith, the plane of the section being in the line 44 of Fig. 1 looking in the direction of the arrow. Fig. 5 is an enlarged detail sectional elevation in the plane of the dotted line 55 of Fig. 2, illustrating the vertically-slotted hanger serving as the guide for the cord-operating pulleys that advance the longitudinally-movable cutter-carriers and operate the expandible cutter-heads, respectively. Fig. 6 is a detail face view of the 60 parts shown by Fig. 5. Fig. 7 is an enlarged view, in end elevation, of the expandible work-head; and Fig. 8 is a detail sectional elevation of said work-head, taken in the plane of the dotted line 88 on Fig. 7. Fig. 9 is a plan view, on enlarged scale, of the pair of opposing cutter-heads to illustrate the several trimming, howeling, and crozing knives, said view also showing the position assumed by one stave of a package when the latter is in operative position relative to the cutters. Fig. 10 is a perspective view of one cutter-head and a part of its carriage detached from the machine. Fig. 11 is a similar view of the other cutter-head. Fig. 12 is a detail vertical section in the plane of the dotted line 1212 on Fig. 9 and taken through the cutter-head which is provided with the crozing-knives. Fig. 13 is a detail perspective view of a stave treated and finished by the machine of my 85 invention.

The same numerals of reference are used to indicate like and corresponding parts in each of the several figures of the drawings.

The horizontal bed or frame 10 of my wood-working-machine may be of any suitable construction adapted to support the several working parts embodied in the construction of the machine; but at a point intermediate of its length this bed or frame is provided with a 90 cross-rail 11, on the upper edge of which is secured the bearing or cap-box 12, which forms one of a series of bearings (not shown) provided in the machine for the support of the horizontal driving-shaft 13. This shaft is arranged in an elevated position longitudinally 95 of the machine, so as to lie above and centrally with relation to the bed, and to an end portion of this shaft is fitted an ordinary clutch-pul-

ley 14 and a stepped or cone pulley 15, said pulleys adapted for the provision of an ordinary driving-belt and means for starting and stopping the shaft, whereby the work may be 5 rotated at variable speeds and the machine thrown out of or into operation at will. This shaft carries a work-holding head which in its entirety is indicated by the numeral 16 in the drawings. This head is skeletonized for 10 lightness in construction, and it is of sectional form to render its parts adjustable for the purpose of expanding or contracting certain elements of the head in order to vary the size and external contour of said head, and thereby 15 adapt the same to the reception of articles which may vary in size and shape. It is to be understood that this rotary head is adapted for the reception of tubs, pails, or other wooden articles which are essentially circular 20 in cross-section; but the expansible work-head has its parts adjusted so that it is immaterial whether the articles to be operated upon are cylindrical or conical in form. As a matter of fact, however, nearly all of the articles to 25 be treated by my machine are of a conical contour more or less—that is to say, they taper longitudinally or vary in diameter at their opposite ends—while at the same time they are circular in cross-section, it being understood 30 that the embodiment of the invention shown by the drawings is especially adapted for treating butter packages, pails, and analogous wooden vessels. For this reason I have shown the expansible head as essentially of conical 35 form; but it is to be understood that this head may be adjusted for the reception of cylindrical articles and that the dimensions and form of the head may be varied within wide limits to suit the different articles or devices 40 on which it may be desired to operate upon in the machine. This expansible head embodies in its construction the disks 17 18, each provided with a collar or hub 19, the latter having the binding-screw 20, and these disks are 45 fitted on the shaft 13 in parallel relation to each other and at a suitable distance apart, the clamping-screws being set against the shaft to make the disks fast therewith. Each disk is provided in its outer face with a plurality of dovetailed grooves 21, which are disposed radially to the imaginary axis of the disk, and the two disks 17 18 carry the two series of radially-disposed arms 22 23, respectively, said arms being fitted in the dovetailed grooves so as to project beyond the peripheral edges of the disks and adapted to slide thereon. The expansible head shown 55 by the accompanying drawings has the disk 17 of greater diameter than the disk 18, and the arms 22 of said larger disk extend beyond the outer ends of the arms 23 on the smaller disk 18 for a purpose which will presently appear. Any suitable means may be provided for clamping each series of arms firmly 60 in place on its disk; but I prefer to employ longitudinal slots 24 in the arms and the bolts 25, which pass through the disk and the slots in the arms, so that the nuts may be tightened for the purpose of firmly holding the arms individually on the disk. The employment of disks of different diameters and the adjustment of the two series of arms to positions wherein the arms of one series extend outwardly beyond the arms of the other series enables a series of bars 26 to be employed, 70 which converge toward one end of the head. These bars lie longitudinally of the head, beyond the circumference of the disks thereof, and are suitably spaced apart to assume positions corresponding to the arms of the two 75 series on said disks, and each longitudinal inclined bar 26 is connected to a pair of the arms 22 23 by means of the pivotal joints 27. It is therefore to be understood that each bar 26 is supported by a pair of arms attached to 80 the respective disks of the head, and the pivotal connection between the individual radially-adjustable arms and the bar enables the arms to be extended more or less beyond the disks in order to give the proper inclination 85 to the bars 26 individually or the convergence of the bars collectively with relation to the axis of the head. The improved construction of the head enables the same to vary for the dual purpose of changing its external contour and the diameter at opposite 90 ends thereof, and this change in the physical characteristics of the head is effected by a few easily-performed adjustments of the parts comprising the head, whereby articles of different dimensions and contours may readily 95 be fitted on the head by slipping the article endwise over the smaller end of same. It is to be noted that the longitudinally-converging bars 26 operate to bind against the inner 100 surface of the cross-sectionally-circular and longitudinally-tapered article, so that the latter will be clamped frictionally on the head, whereby the article is made to rotate with the head when the shaft 13 is in motion. 110

28 29 designate transverse guides, which are arranged in horizontal positions on one side of the bed or frame 10 to extend outwardly therefrom. These guides are arranged parallel to each other in planes on opposite sides 115 of the work-head 16, as shown by Figs. 1 and 2, and said outwardly-extending guides are braced into position by the inclined struts 30, which are fastened to the guides and a side rail of the bed or frame 10. (See Figs. 2, 3, 120 4.) Each guide consists of two members or parts, which are braced by a corresponding number of struts; but the detailed construction of these parts is not material. 125

In my machine I employ two cutter-heads, which are adapted to be presented to the opposite end portions of the work to be operated upon, one cutter-head being equipped with knives which trim the end edge of the work and the inner and outer faces of the 130 staves thereof, while the other cutter-head is equipped with a plurality of knives which are fashioned and arranged to croze the inner surface of the work adjacent to the edge, 135

to howel the staves, and to trim the end edges of the staves, all as will hereinafter appear. These two cutter-heads are capable of a compound movement with respect to the work-head—that is to say, the cutter-heads are capable of a movement longitudinally of the machine and simultaneously in opposite directions in order to advance said heads toward or from the article on the work-head—
 5 and said cutter-heads are also capable of a simultaneous movement transversely to the axial plane of the work-head in order to move the cutter-heads laterally to and from the article on the work-head for the purpose of moving the cutter-heads out of operative position, so that the work may be placed on or removed from the work-head without hindrance from said cutter-heads. The transverse movement of the cutter-heads is effected by the employment of slidable carriers 31 32, which are fitted, respectively, in the guideways 28 29. (See Fig. 1.) These carriers are in the form of horizontal slides, which are free to move in the guideways 28
 10 29 in a direction transverse to the machine and toward or from the work-head, the axis of which is common to the longitudinally-arranged driving-shaft 13. Said slidable carriers are provided near their inner ends with
 15 the guideways 33, (see Fig. 4,) said guideways being arranged at right angles to the axis of the transversely-movable carriers, and thus lying in the direction of the length of the machine. In the guideways 33 of the transversely-movable carriers are slidably confined the cutter-carriers 34 35, the latter being arranged and movable in said guideways longitudinally of the machine, so as to travel toward or from the ends of the article
 20 on the work-head. It is therefore to be understood that the slidable carriers 31 32 move the cutter-carriers transversely across the machine and laterally with respect to the work-head; but these cutter-carriers are capable of a slidable movement in the guides 33 in the direction of the length of the machine. The cutter-carriers 34 35 are normally drawn away from each other and from the end portions of the article on the work-head
 25 by means of weighted cables 36, each cable being fastened securely to an arm 37, which is fastened to the front end of the cutter-carrier. The cable is guided around one member of a double sheave 38 39, pivoted on one
 30 transversely-movable carrier 31 or 32 and around a sheave 38^a on a fixed guide for said carrier, and thence around a sheave 40, which is mounted on a fixed arm 41 of the framework. Each cable for the longitudinally-movable
 35 cutter-carrier is guided by the sheaves described, so as to be out of the way of other operating parts of the machine, and a drop-weight 42 is fastened to a depending length of this cable 36, the tendency of the drop-
 40 weights of the two cutter-carriers being to normally pull said cutter-carriers away from each other.

A depending arm 43 is fastened securely to each transversely-movable slide, so as to lie between the pair of inclined struts 30, and to the arms of the respective slides 31 32 are individually fastened the cables 44, each having a drop-weight 45, whereby the weighted cables normally pull on the slides or carriers 31 32 to move the latter and the devices mounted thereon in a direction transversely across the machine and laterally and away from the work on the work-head. Each cable 44 passes over a sheave 46, which is loosely journaled on an arbor 47, supported in the inclined struts 30, provided for bracing the members of the guideway for the transversely-movable carrier to which the cable is attached.

I have provided means for simultaneously moving the transversely-movable carriers 31 32; but such means is connected individually and adjustably to the arms 43 of said carriers in a manner to provide for variation in the position of the slides and the cutter-heads thereon, so as to compensate for the variation in the diameter at opposite ends of the article under treatment in the machine. A pair of slidable bars 48 are fitted in suitable openings or slots 49 in depending rails of the horizontal frame or bed 10, said bars being arranged in overlapping relation to the depending arms 43 of said carriers 31 32. The bars are supported in the frame or bed to be movable in rectilinear paths across the same, each bar having a series of apertures 50, in either one of which may be fitted a connecting-pin 51, that serves to fasten the depending carrier-arms 43 adjustably to the slidable bar 48. A connecting-bar 52 is fastened to the slidable bars 48, so as to insure simultaneous movement to the pair of bars 48, and as the arms 43 are attached to the slidable bars and to the transversely-movable carriers 31 32 it is evident that the motion of the bars 48 will be communicated by the arms 43 to the carriers 31 32, although said carriers may be adjusted individually on the bars by means of the pins 51. A coiled spring 53 is fastened to a suitable part of the frame or bed and to the connecting-bar 52, and this spring tends to normally draw the connecting-bar in the same direction that the drop-weights 45 pull the carriers 31 32. This spring is arranged centrally with relation to the connecting-bar so as to exert stress thereon in a manner which prevents binding of the parts in a practical operation of the machine. An adjusting-cable 54 is fastened to the connecting-bar 52 in any suitable way, and this cable is associated with hand-operated adjusting devices adapted to move the connecting-bar 52 and the carriers 31 32 against the tension of the retracting-spring 53 and the gravity of the drop-weights 45, whereby the carriers 31 32 and the cutter devices thereon may be drawn toward the article on the work-head. An arbor or spindle 56 is journaled in any suitable way on one side of the machine frame or bed and a drum or

sheave 57 is mounted on this arbor, the cable 54 being fastened in any suitable way to the sheave. (See Fig. 3.) A series of transverse openings 58 is provided in the sheave 57, in either one of which may be fitted a connecting-pin 59 for the purpose of adjustably connecting a lever 60 to the sheave, said lever being fitted loosely on the arbor or spindle 56, so that its axis of movement is coincident with the axis of the sheave. It will be seen that the pin connects the lever adjustably with the sheave in a manner to make the sheave turn with the lever when the latter is operated by hand in order to draw on the cable 54 and adjust the bars 48 and the slideable carriers 31 32, and this lever is equipped with a latch 60^a, which may fit in any one of the series of notches in a segment 61, that is fastened securely to a side of the machine bed or frame, whereby the lever may be locked in place in order to confine through the intermediate mechanism the slideable carriers in their adjusted positions with relation to the work-head.

62 designates a vertical hanger which is securely fastened to a side of the machine-bed in a position equidistant from the transverse guideways 28 29, and this hanger extends below said bed and above the upper face thereof. (See Figs. 2 and 3.) The hanger is provided with a longitudinal slot 63, adapted for the accommodation of the adjusting-levers 64 65, the former of which operates devices that tend to move the cutter-carriers longitudinally of the machine and inwardly toward the end portions of the article on the work-head, while the last-named lever 65 actuates devices that close the jaws of the sectional cutter-heads upon the end portions of the article subsequent to the inward movement of the cutter-heads toward each other and said end portions of the article. The lever 64 is fulcrumed in a suitable way on the outside of the machine-bed, so as to have one end extend through the slot in the lower part of the hanger, and this end of the lever is connected to a sheave-block 66, in which is supported the spindle for the sheave 67. On the hanger 62, near its upper end, is loosely journaled a pair of idle guide-sheaves 68, which are supported on horizontal pins attached to the hanger so as to have their opposing edges disposed on opposite sides of the vertical axis of said hanger. A carriage-operating cord 70 is fastened at one end to an arm 71 on the cutter-carriage 35, from thence passes over one guide-sheave 68, thence passes downwardly and beneath the sheave 67, which is movable with the adjusting-lever 64, thence passes upwardly and over the other guide-sheave 68, and is finally extended to an arm 72, which is made fast with the other cutter-carriage 34. It is obvious that the end portions of the cord 70 are fastened to the cutter-carriages, while the intermediate looped part of the cord fits under the vertically-movable sheave 67, whereby a downward movement of the lever and the

sheave 67 operates to strain the cord 70 for the purpose of moving the cutter-carriages inwardly toward each other simultaneously and against the gravity of their drop-weights 70 and 75. The carriage-operating cord 70 has its lengths on opposite sides of the sheave 68 guided by the rollers 38 39 on the slideable carriers 31 32 and by the small sheaves 73 74, 75 attached to the guideways 28 29. (See Fig. 1.)

The end of the lever 65 is forked, as at 75, and connected by a pin 76 to a sheave-block 77, the latter having a part 77^a thereof fitted in the guideway 78 of the hanger 62. On this sheave-block is supported the arbor of a cord-operating sheave 79, the latter being arranged above and in a vertical plane to one side of the sheave 67 for the carriage-cord 70. The pair of small sheaves 80 are journaled on the upper extended part of the hanger, so as to lie above the sheave 79 and the guide-sheaves 68 for the carriage-cord, for a purpose which will presently appear.

In my machine I employ cutter-heads of 9c sectional construction, each head adapted to have its jaws or members opened and closed in order that the cutters may be spread for the purpose of permitting the end edge of the work to enter the space between the jaws. 95 The jaws for the cutter-head on the carriage 34 are indicated by the reference-numerals 81 82, while the jaws for the cutter-head on the other side of the cutter-carriage 35 are indicated by 83 84. Each cutter-head has its 100 curved jaws connected by a link 85, which has its end portions pivotally attached at 85^a to the jaws and to the cutter-carriage, thus confining the jaws on said carriage in a manner which permits said jaws to be opened and 105 closed. The shanks of the jaws are extended beyond the pivotal connection with the links for the reception of a spring 86, which operates normally to separate the ends of the 110 jaws on which the cutters are mounted, and between the shanks of these jaws is disposed a cam 87. A bolt 88 confines the cam on the cutter-carriage, and the cams for the two cutter-heads are actuated by levers 89 90. A cord 91 is fastened to the lever 89 and extends 115 over one of the sheaves 80, around the sheave 79, which is actuated by the lever 65, thence upwardly to and around the other sheave 80, and is then fastened to the lever 90. By operating the lever 65 to depress the sheaves 79 the cord 91 is strained to move the levers 89 90 inwardly toward each other in the direction indicated by the arrow in Fig. 1, and the cams 87 are thus operated to spread the shanks of the jaws against the tension of the retracting-spring 86 for the purpose of closing the jaws and the cutters upon the work. It is obvious, however, that the jaws of the cutter-heads should remain in their open or spread conditions until the carriages 31 32 shall have 125 been moved toward the work-head and the cutter-carriages, with the cutters thereon, shall have been drawn inwardly toward the 130 end portions of the article on the work-head.

Before proceeding to a description of the construction and arrangement of the knives I will first describe the stave in its finished condition after treatment by my improved machine, said stave being shown by Figs. 9 and 13 and being representative of each of the other staves which when assembled in proper relation constitute the package or article which is fitted on the work-head for treatment in the machine. It is to be understood that the staves are assembled in circular series and in an unfinished condition to produce the body of the package which is to be fitted upon the work-head, and said unfinished staves of the package are treated simultaneously during the rotation of the work-head, so as to have the faces and edges of the staves finished, as shown by Figs. 9 and 13. This stave is indicated at 120. On the inner face of the stave, at one end thereof, the stave has the howeled curved surface 121, and the croze 122 is cut transversely across this howeled inner surface of the stave. The end edge of the stave, at the howeled portion thereof, is trimmed, as at 123, and the opposite end edge of the stave is also trimmed at 124, thus producing smooth finished edges at opposite ends of the stave. At the end of the stave opposite to the howeled surface 121 the inner face of said stave is beveled or curved at 125, and the outer face of the stave is curved, as at 126, the end edge 124 of the stave being trimmed between these beveled or curved surfaces 125 126. From this description of the stave it will be apparent that a plurality of knives or cutters on the two cutter-heads must be employed for the proper operation on the inner and outer surfaces and the end edges of the staves, and I have fulfilled this condition by a simple and efficient arrangement of knives, which are arranged in a novel manner so as to be properly presented to the appropriate faces and edges of the package.

The cutter-carriage 34 is equipped with the crozing-knives, the howeling-knife, and a trimming-knife suitable for forming the howel 121, the croze 122, and the trimmed edge 123 on the staves of a package, at one end thereof. This carriage 34 is provided between the free ends of the jaws 83 84 with a fixed knife-block 92, which extends above the horizontal plane of the jaws, and this knife-block is provided with a seat-face 93, the same being inclined downwardly toward the plane of the carriage. On this knife-block is fitted the edge-trimming knife 95, which is held firmly in place by a set-screw 97 or other suitable clamping device, whereby the edge-trimming knife is held in a position inclined to the plane of rotation of the work. This inclined knife 95 has its cutting edge 98 inclined to the longitudinal axis of the knife-body, and said knife may be projected more or less beyond the knife-block, so as to make its cutting edge 98 operate with a draw cut on the end edges of the staves. The knife-block 92 is provided with a recess 99, in which the jaw

84 of the cutter-head is free to move in order to approach and recede from the complementary other jaw of the cutter-head, and this jaw 84 is also provided at its free end with an abutment 110, which is adapted to bear frictionally against the outer surface of the package when the two jaws of the cutter-head are closed in order to properly present the knives or cutters to one end of the package. The other jaw 83 of this cutter-head on the carriage 34 is provided at its free end with a knife-block 100, which is disposed in the horizontal plane of and in opposing relation to the abutment 110 on said jaw 84, and this knife-block is integral with the jaw 83 or is firmly fastened thereto, so as to move therewith. The knife-block 100 is provided on its upper face with an inclined seat 101, and said knife-block is furthermore provided with a transverse slot 102. The howeling-knife 103 is fitted laterally against the inclined seat-face 101 of the movable knife-block, so as to be presented to the work in an inclined position, said knife being held firmly in place by a clamp 104, which is shown in the form of a binding-screw. The howeling-knife 103 is provided with the curved cutting edge 105, and this howeling-knife is movable with the jaw 83 and the knife-block 100, so as to be carried thereby into overlapping relation and above the edge of the edge-trimming knife 95. The howeling-knife is thus presented in an inclined position to the inner surfaces of the staves at one end of the package, and the curved edge 105 of this knife is operable on the staves to produce the howeled surface 121 thereon. I employ a pair of crozing-knives 106 107, which are fitted in the slot 102 of the movable knife-block, and these knives have their inner beveled ends 108 extended beyond the inner face of this knife-block, so as to lie below the cutting edge of the howeling-knife 103 and opposite to the working edge of the edge-trimming knife 95. The crozing-knives are held in place within the slotted knife-block by a suitable clamp 109, and these knives may be individually adjusted in order to project them for proper distances to cut the croze 122 in the staves. It is to be observed that the howeling and crozing knives are both carried by one jaw of the cutter-head on the carriage 34, while the edge-trimming knife is on the carriage itself, and the other jaw of the cutter-head is provided with an abutment 110, which is opposite to the howeling and crozing knives. When the cam is turned in line with the jaws, the spring closes the shanks together and opens the working ends of the jaws, so as to separate the abutment 110 and the crozing and howeling knives laterally, thus permitting the ends of the staves in the package to be received in the space between the abutment and the said knives on the movement of the carriage 34 toward the work on the revoluble head, after which the cam is operated in a manner to close the jaws for the abutment to bear against the

outer surface of the package, the crozing and howeling knives to operate on the inner surface of the staves, and the edge-trimming knife to cut the end edges of the staves. The other cutter-carriage 35 is provided with a knife-block 111, having the edge-trimming knife 112, similar to the knife-block 92, and the knife 95 on the carriage 34. The jaw 82 of this cutter-head on said carriage 35 is provided with a lug 113, forming an inclined seat for a beveling-knife 114, the same being held in place by a suitable clamp 115. This beveling-knife has its working edge presented in an inclined position to the outer face of the staves at the other end of the package. The jaw 81 of said cutter-head on the carriage 35 is provided with a short post 116, having an inclined seat-face 117, and on said seat-face is fitted the howeling-knife 118, the latter being clamped in place and having the curved cutting edge 119. The knives 118 114 operate on the inner and outer faces of the staves in the package, so as to produce the inner and outer curved surfaces 125 126, and it is to be observed that the jaws 81 82 of the cutter-head on the carriage 35 are provided with the face trimming and howeling knives, respectively, which are adapted to approach each other and the work when the jaws are closed by the action of the cam.

The operation may be described as follows: The work is forced on the revoluble head, so as to rotate therewith. The operator first adjusts the lever 60 to move the slides 31 32, the cutter-carriages, and the cutter-head laterally across the machine until the cutter-heads are in line with the package, the jaws of the cutter-heads being open. The lever 64 is now manually operated to strain the cord 70 and move the cutter-carriages toward each other until the edge-trimming knives thereon are in position to work on the end edges of the staves, and, finally, the lever 65 is manually operated to draw on the cord 91 and move the arms 89 90, so as to operate the cams and simultaneously close the jaws of the two cutter-heads, whereby the howeling-knife 103 and the crozing-knives on the cutter-head of the carriage 34 are operatively related to the inner surface of the staves at one end of the package, and the beveling and howeling knives on the cutter-head of the carriage 35 are brought into proper position for operation on the inner and outer surfaces of the staves at the other end of the package. These knives serve to howel, croze, finish, and trim the staves to reduce them to the condition shown by Fig. 13 at one operation in the machine. Previous to removing the work the carriages are retracted and moved laterally, and the revoluble head is then arrested.

It will be understood by reference to the drawings that the levers 60 64 65 are within convenient reach of the operator stationed on the side of the machine opposite the carriages and cutter-heads and that said levers

are manually operated when the machine is in use.

Changes in the form and proportion of parts 70 may be made without departing from the spirit of the invention.

Having thus described the invention, what I claim is—

1. The combination of a revoluble work-head, a pair of carriages movable at right angles to the axis of the work-head, connections to simultaneously move said carriages, cutter-heads on said carriages, movable toward and from each other, connections to simultaneously move said cutter-heads, a pair of pivoted jaws on each of said cutter-heads, the jaws of each of said pairs having work-engaging faces and howeling-knives and connections to simultaneously close the said pairs 85 of jaws, substantially as described.

2. The combination with a revoluble work-head, of transversely-movable carriages, connections between said carriages to move the latter simultaneously, said carriages being 90 adjustable independently of each other on said connections, work-heads on said carriages, and movable toward and from each other, and connections to move said work-heads simultaneously, substantially as de- 95 scribed.

3. In a woodworking-machine, the combination of a revoluble work-head, transversely-movable carriages having cutter-heads movable therewith, said cutter-heads being mov- 100 able on said carriages toward and from each other and a carriage-adjusting mechanism for moving said carriages simultaneously, said adjusting mechanism having adjustable connection individually with said transversely- 105 movable carriages, substantially as described.

4. In a woodworking-machine, the combination of a revoluble work-head, transversely-movable carriages, bars connected with said carriages, means for normally impelling the 110 carriages in one direction, a lever for simultaneously moving said carriages against the action of the retracting devices, cutter-heads mounted on the carriages and movable toward and from the work-head and connections to 115 simultaneously move said cutter-heads, sub- stantially as described.

5. In a woodworking-machine, the combination of a revoluble work-head, transversely-movable carriages, slideable bars connected 120 for simultaneous movement and connected adjustably and individually with said carriages, means for adjusting the slideable bars, cutter-heads mounted and movable on the carriages for presentation to the work-head, 125 connections to simultaneously move said cutter-heads, pivoted jaws on said cutter-heads and having crozing and howeling knives and means to simultaneously operate said pivoted jaws, substantially as described.

6. In a woodworking-machine, the combination of a revoluble work-head, transversely-movable carriages, bars connected to said carriages, cutter-carriages movable longitudi-

nally on the transversely-movable carriages, a sheave having a flexible connection with said bars, and a lever connected adjustably with the sheave and provided with a locking contrivance, substantially as described.

7. In a woodworking-machine, the combination of a work-head, transversely-movable carriages, cutter-carriages movable transversely on the transversely-movable carriages, bars connected with said carriages, retractors for the carriages, a revolute element having a flexible connection with said bars, and a lever adjustably connected with the revolute element and provided with a locking contrivance, substantially as described.

8. In a woodworking-machine, the combination of a work-head, transversely-movable carriages, means for simultaneously moving said carriages, cutter-carriages mounted in the first-named carriages and supporting cutter-heads, means for simultaneously moving said transversely-movable carriages, means for simultaneously moving said cutter-carriages and independent adjusting devices for the transversely-movable carriages, substantially as described.

9. In a woodworking-machine, the combination of a revolute work-head, cutter-carriages supporting spaced cutter-heads, a lever carrying a sheave, and a cord attached to the carriages and fitted to the sheave, substantially as described.

10. In a woodworking-machine, the combination with a work-head, of transversely-movable carriages, cutter-carriages, on said transversely-movable carriages, normally-open cutter-heads on said cutter-carriages, and means for simultaneously closing the cutter-heads, substantially as described.

11. In a woodworking-machine, the combination with a work-head, of cutter-carriages, normally-open cutter-heads on said carriages, a lever, and connections from said lever to both cutter-heads for simultaneously closing the latter, substantially as described.

12. In a woodworking-machine, the combination with a work-head, and cutter-carriages, of a pair of spaced cutter-heads on said carriages and each having spring-controlled jaws, cams adapted to open the jaws, levers connected with the cams, a hand-lever, and connections between the hand-lever and said cam-levers, substantially as described.

13. In a woodworking-machine, a cutter-head consisting of a pair of jaws pivotally

mounted on said cutter-head, one of said jaws having crozing and howeling knives, a spring connecting the jaws to normally close the same, and a cam adapted to spread the jaws against the action of the spring, substantially as described.

14. In a woodworking-machine, a work-head consisting of parallel members, a series of bars, and means connecting said bars with said parallel members, substantially as described.

15. In a woodworking-machine, a work-head consisting of disks provided with radial grooves, arms clamped individually in said grooves, and longitudinal bars pivoted to said arms, substantially as described.

16. In a woodworking-machine, an expandable work-head comprising a pair of disks, a series of longitudinal bars, two series of arms connected with said longitudinal bars, and means for clamping the arms of each series to one of the disks, substantially as described.

17. In a woodworking-machine, an expandable work-head comprising a pair of disks, two series of radially-disposed arms clamped individually to said disks, and a series of longitudinal bars connected pivotally with the arms and supported thereby beyond the circumference of the disks, substantially as described.

18. A cutter-head having an edge-trimming knife secured thereto, pivoted jaws to clamp the sides of the work, said jaws being adapted for the attachment of cutting-tools to operate on the sides of the work and having extended shanks or arms, a cam disposed between said shanks or arms and an operating-lever attached to said cam, substantially as described.

19. In a machine of the class described, the combination with a revolute work-head of a transversely-movable carriage a longitudinally-movable carriage on said transversely-movable carriage, a cutter-head on said longitudinally-movable carriage, said cutter-head having an edge-trimming knife and a pair of pivoted jaws for engaging and operating on the sides of the work, substantially as described.

In testimony that I claim the foregoing as my own I have hereto affixed my signature in the presence of two witnesses.

LOUIS D. VOGEL.
